FOLDER FOR SEWING MACHINES

Rudolph J. Sailer, Townley, N. J., assignor to
The Singer Manufacturing Company, Elizabeth, N. J., a corporation of New Jersey

Application March 29, 1933. Serial No. 663,307

6 Claims. (Cl. 112—138)

This invention relates to attachments for sewing machines and more particularly to folders therefor.

The features of the invention and the advantages attained thereby will be readily understood by those skilled in the art from the following detailed description of a preferred embodiment of the invention, taken in connection with the accompanying drawings, in which:

10 Figure 1 is a front elevation of the well known "Singer" multiple needle chain-stitch sewing machine showing my improved folder fixed thereto.

15 Figure 2 is a top plan view of a portion of the sewing machine provided with the present invention.

Figure 3 is a rear elevation of the folder and its support.

Figure 4 is a sectional view taken along the line 4—4 of Figure 2.

20 Figure 5 is a sectional view taken along the line 5—5 of Figure 2.

Figure 6 is a disassembled perspective view of the folder.

The present improvement is shown applied to 25 the well known "Singer" sewing machine of the type known commercially as the "109" class machine. The machine comprises a frame having a base 1, standard 2, and overhanging bracket-arm 3 which terminates in a hollow head 4 wherein 30 the reciprocating needle-bar 5 carrying the needles 6 and the presser-bar 7 carrying a presser-device 8 are journaled. Located below the cloth-plate 9 are the loopers 11 which are actuated by the main-shaft 10 and cooperate with the needles 35 6 in the formation of stitches.

My improved supporting means for the folder comprises an arm 12 pivotally secured by the shouldered screw 13 to the base or bed-plate 1 for swinging movement in a horizontal plane. 40 Pivotally secured to the arm 12 by the pivot screw 14 is a supporting bracket 15 having my improved folder, indicated generally at 16, adjustably secured thereto by means of the elongated slots 17 and the screws 18. To partially restrain and to limit the movement of the bracket 15 about its pivot 14 I have provided the bracket 15 with a knurled headed shouldered screw 19 extending through the elongated slot 19' in the arm 12, the screw 19 being threaded into the bracket 50 15.

In some types of material, such as blankets, the nap on the top extends in a direction opposite to the nap on the bottom. When applying binding to the edges of this type of material the nap on 55 one side tends to force one limb of the binding

strip outwardly and the nap on the other side tends to draw the other limb inwardly. To overcome this crawling effect and to insure that the binding strip will be bent accurately about the edge of the work so that the seam may come at an equal distance from each edge of the binding strip I have threaded an adjusting screw 20 into the depending lug 15' formed on the bracket 15. The adjusting screw 20 is formed with a flange 21 which is received by the slot 22 formed between the two upstanding ears 23 on the arm 12. It will be obvious from the foregoing that movement of the screw 20 causes the bracket 15 to swing about the pivot-pin 14 thereby moving the delivery end of the folder 16 in the arc of a circle and relative to the stitch-forming mechanism.

In its preferred embodiment, my improved binder comprises an inner U-shaped guiding element 25 and an outer U-shaped guiding element 26 which are spaced apart to form a passageway for the binding strip. The guiding elements 25 and 26 are cut away at their forward or front ends to form an inclined edge 25' and 26' and the inner element 25 is provided with a curved inner wall 35 for the reception of the binding strip as it is reversed, as is well known in this art. The guiding elements are mounted on a shank 27 disposed between the arms 25' of the inner U-shaped member 25. Upper and lower guide-plates 28 and 29 are pivoted intermediate their ends between the U-shaped guiding elements 25 and 26 by the pivot-screws 30 and the members 25 and 26 are held in engagement with the guide-plates 28 and 29 by means of the screws 37 and 38 which extend through the elongated slots 39 and 40 formed in the guide-plates 28 and 29. At the receiving end of the binder the guide-plates 28 and 29 are connected by a yoke 31 formed with a notch 32 which receives a thumb-screw 33 threaded into the shank 27 and provided with a shoulder 34 and a flange 35 which engage opposite sides of the yoke 31. By adjusting the thumb-screw 33, the guide-plates 28 and 29 are swung about their pivot-pins 30 to contract or expand 100 the strip passageway at the delivery end of the binder for accommodation of strips of various widths.

Having thus set forth the nature of the invention, what I claim herein is:—

1. In a binder of the class described, in combination, a guiding element, a second guiding element enclosing and spaced from said first guiding element, upper and lower edge-guides disposed between and pivotally secured to said guid- 110

- ing elements, and means for moving said edge-guides about their pivots, whereby the binder may be adjusted to accommodate binding strips of various widths.
5. In a binder of the class described, in combination, a guiding element, a second guiding element enclosing and spaced from said first guiding element, a pair of edge-guides disposed between and pivotally secured to said elements, and 10 a single means for swinging said edge-guides about their pivots, whereby the passageway at the delivery end of the binder may be varied to accommodate strips of various widths.
3. A folding attachment for sewing machines, 15 comprising a shank, an inner U-shaped guiding element secured to said shank, an outer U-shaped guiding element spaced from and enclosing said first mentioned guiding element so as to form a passageway for a binding strip, edge-guides disposed within the space between and pivoted to said guiding elements, and means for 20 moving said edge-guides relative to said guiding elements.
4. In a folder of the class described, in combination, a folding element, a second folding element spaced from and enclosing said first mentioned folding element, a pair of edge-guides

disposed between and pivoted to said folding elements, a web connecting said guides, and a screw received by said web for concomitantly swinging said edge-guides about their respective pivots.

5. In combination with a sewing machine having a frame including a bed and stitch-forming mechanism, a binder for guiding a binding strip in two horizontal parallel layers which are connected by a U-shaped bend to the stitch-forming mechanism, an arm supporting said binder, means for pivotally securing said arm to the bed of the machine, and a thumb-screw for moving said binder in a vertical arc about its pivotal connection.

6. In combination with a sewing machine having a frame including a bed and stitch-forming mechanism, a bracket pivoted to the bed of the machine for swinging movement in a horizontal plane, an arm pivoted to said bracket, a thumb-screw for moving said arm in a vertical plane about its pivot, a shank adjustably secured to said arm and a binding folder carried by said shank, said folder comprising inner and outer guiding elements between which are interposed pivoted edge-guides and an adjusting screw for varying the position of said edge-guides.

RUDOLPH J. SAILER.
